UNITED STATES PATENT OFFICE.

JOHN DANIEL, OF MILWAUKEE, WISCONSIN, ASSIGNOR TO KOEHRING MACHINE COMPANY, OF MILWAUKEE, WISCONSIN.

CONCRETE-MIXING MACHINE.

Specification of Letters Patent. Patented Jan. 15, 1918.

1,253,945.

Application filed May 31, 1917. Serial No. 171,993.

To all whom it may concern:

Be it known that I, JOHN DANIEL, a citizen of the United States, residing at Milwaukee, in the county of Milwaukee and

5 State of Wisconsin, have invented certain new and useful Improvements in Concrete-Mixing Machines, of which the following is a specification.

This invention embodies certain improvements in concrete mixing and distributing machines. The invention has to do primarily with the concrete mixer and certain associated loading and discharging means for said mixer, all of which are commonly employed today in many types of mixers at the present upon the market. In these mixing machines it is usual to employ a rotary mixing drum adapted to be loaded or charged at one end by means of a loading skip which 10 receives the aggregates at the ground level and is thereafter elevated to supply the desired charge of aggregates to the mixer. The mixing drum is customarily discharged from the end opposite that into which the 15 aggregates are fed by the loading skip and suitable discharge controlling means are utilized for the discharge purpose.

The improvements hereinafter described involve the utilization of certain instrumentalities co-operatively associated with the loading skip and with the discharge controlling means whereby to insure an adjustment of the latter to a position preventing discharge action of the drum, preliminary to the feeding of the aggregates into the drum by the loading skip.

In the more specific embodiment of the invention the discharge means employed by me is a common type, namely a discharge chute located at the outlet end of the mixing drum and adapted to be positioned so as to permit and to prevent discharge of the aggregates which are customarily elevated in the drum and dropped upon the discharging chute when the latter is in its discharging position. Should the discharging chute be in its discharging position when the aggregates are fed into the drum of the loading skip it is evident that there is a 40 possibility of premature discharging of the aggregates. It is to avoid the likelihood of premature discharge that I employ suitable operating devices mounted on the frame of the machine and adapted to be actuated by 45 the loading skip as it is raised to its drum

charging position, these operating devices being geared to the discharging chute so as to forcibly move the latter into a non-discharging position prior to the feeding of the aggregates into the mixer. 60

The invention involves, supplemental to the foregoing main features, certain details of construction which will appear more fully upon reference to the following description in connection with the accompanying 65 drawings, in which:

Figure 1 is a side elevation of a well known type of concrete mixing and distributing machine and illustrating the discharge controlling instrumentalities intermediate the discharge chute and the loading skip. 70

Fig. 2 is an enlarged view as compared with Fig. 1, showing more particularly the actuating means between the loading skip 75 and discharge chute, certain main portions of the machine being shown in dotted lines.

Fig. 3 is an end view of the machine looking toward the discharge chute and bringing out more fully the relative arrangement and 80 constructions of the manual and automatic operating devices.

For the purposes of this description it will suffice to state that the mixing and distributing machine to which the present invention is applied is known as the Koehring paver and embodies the customary supporting truck adapted to be driven under its own power by the provision of a suitable motor thereon, said truck including a frame A at 90 one end of which is located the loading skip B. The skip B is adapted to be raised by any suitable mechanism which has no bearing upon this invention, and when raised aggregates placed in the skip at the ground 95 level will be discharged into the mixing drum D carried by the frame A. From the drum D the mixed materials are adapted to be discharged by the discharge chute C which is pivoted on the frame in such a manner that 100 when its outer end is raised the chute is inactive so far as discharging is concerned, but when the position of the chute is reversed so that it inclines downwardly at its outer end materials constantly being elevated in the drum D are adapted to drop upon the chute C and to be deflected out of the drum into any receptacle or distributing device. 110

The actuating instrumentalities between 1

the skip B and the chute C comprise an operating bar 1 mounted for horizontal sliding movement on the frame A by the provision of suitable bearings therefor. Carried by the skip B is an abutment 2 adapted to impinge the bar 1 and to force it longitudinally toward the discharging end of the drum D, this action taking place just previous to the discharging of the aggregates 10 from the skip B into the drum incident to the elevation of the skip.

A cable 3 is connected at its opposite ends to the bar 1 at spaced points in the length of the latter and one end portion of said 15 cable passes in one direction around a pulley 4 and the other end passes in an opposite direction around a pulley 5, these pulleys being coaxial and supported by the frame A. At its middle portion the cable 3 is looped 20 about a grooved element 6 fixed on or integral with a bevel gear 7 which is likewise fixed to the shaft 9 which forms the pivotal support for the chute C and by which the chute is adapted to be tilted into dis- 25 charging or non-discharging positions. There is employed a manual operating device for the chute C in the form of a bevel pinion 8 carried by a shaft 10 supported in suitable bearings on the frame work and 30 diagonally arranged respecting the shaft 9. The pinion 8 meshes with the bevel gear 7 and a crank handle 11 is carried by the shaft 10 whereby the latter may be turned manually to move the chute C to 35 its discharging position. The chute C of course is returned to its non-discharging position by operation of the manual device aforesaid but should this be overlooked by the operator in the use of the machine it will 40 be evident that owing to the operating provisions that have just been described, as the skip B is elevated the bar 1 will be operated to actuate the cable 3 in such a manner that the chute C will be caused to assume a non- 45 discharging position before a new batch of materials is introduced into the mixer by the skip B. The pulleys 4 and 5 are independent of one another so that they may rotate positively when the cable 3 is actuated and 50 the cable is frictionally engaged with the grooved member 6 to insure the proper operation of the devices as described.

Having thus described my invention, what I claim as new is:—

55 1. In a mixing machine, the combination with a mixer, a charging device therefor and means whereby to effect discharging of the contents of the mixer, of an operating bar adapted to be actuated during charging 60 movement of the charging device, and gearing between said bar and the discharging means aforesaid whereby to effect a non-discharging adjustment of the latter when the operating bar is actuated.

65 2. In a mixing machine, the combination

with a mixer, a charging device therefor and means whereby to effect discharging of the contents of the mixer, said discharging means comprising a discharge chute movable into discharging and non-discharging 70 positions, of an operating bar shiftable by the charging device as the latter moves to charge the mixer, and cable driving instrumentalities intermediate said bar and the chute.

3. In a mixing machine, the combination with a mixer, a charging device therefor and means whereby to effect discharging of the contents of the mixer, said discharging means comprising a discharge chute movable 80 into discharging and non-discharging positions, of an operating bar shiftable by the charging device as the latter moves to charge the mixer, cable driving instrumentalities intermediate said bar and the chute 85 including a cable having its ends fixed to the operating bar at spaced points in the length of the latter, a grooved member frictionally engaged by a looped portion of said cable, and a connection between said 90 grooved member and the chute whereby the latter may be moved as an incident to actuation of the grooved member by the cable.

4. In a mixing machine, the combination with a mixer, a charging device therefor and 95 means whereby to effect discharging of the contents of the mixer, said discharging means comprising a discharge chute movable into discharging and non-discharging positions, of an operating bar shiftable by the 100 charging device as the latter moves to charge the mixer, cable driving instrumentalities intermediate said bar and the chute, and a manual device also adapted to operate said chute.

5. In a mixing machine, the combination with a mixer, a charging device therefor and means whereby to effect discharging of the contents of the mixer, said discharging means comprising a discharge chute movable into discharging and non-discharging positions, of an operating bar shiftable by the charging device as the latter moves to charge the mixer, cable driving instrumentalities intermediate said bar and the chute, 110 and manual means for actuating the chute including a shaft and a train of gearing intermediate said shaft and said grooved member.

6. The combination with a mixing machine embodying a mixer, a loading skip adapted to be elevated to charge the mixer, and a discharge chute movable into discharging and non-discharging positions, of an operating bar supported adjacent to the skip, means on the skip for shifting said bar longitudinally as the skip is raised, a shaft connected with the chute to actuate the same, a gear fixed to said shaft and having a grooved element connected therewith, a 125 130

cable attached to said bar at spaced points, 5 separate pulleys about which said cable passes in opposite directions, the cable being looped intermediate its ends about the grooved element aforesaid whereby as the bar is moved said grooved element, its gear and the connected shaft will be actuated.

7. The combination with a mixing machine embodying a mixer, a loading skip 10 adapted to be elevated to charge the mixer, and a discharge chute movable into discharging and non-discharging positions, of an operating bar supported adjacent to the skip, means on the skip for shifting said bar 15 longitudinally as the skip is raised, a shaft

connected with the chute to actuate the same, a gear fixed to said shaft and having a grooved element connected therewith, a cable attached to said bar at spaced points, 20 separate pulleys about which said cable passes in opposite directions, the cable being looped intermediate its ends about the grooved element aforesaid whereby as the bar is moved said grooved element, its gear and the connected shaft will be actuated, 25 and manual means for operating said chute including a pinion meshing with the gear and an operating shaft for said pinion.

In testimony whereof I affix my signature.
JOHN DANIEL.
